UNITED STATES PATENT OFFICE.

WILLIAM VENNARD, OF LONDON, ENGLAND.

LOOSE-LEAF BINDER.

Application filed January 13, 1927, Serial No. 160,831, and in Great Britain February 15, 1926.

This invention relates to loose-leaf binders of the thong type, in which a thong stretcher bar is actuated by a screw or the equivalent mounted in one of the covers and extending between the front and back edges thereof.

In binders of this type a construction has been proposed in which the stresses set up by the tightening operation are localized in a bar fixed to the inner edge of one of the covers. Further a construction has been proposed in which the stresses set up by the tightening operation are distributed over the whole of the cover and is not confined to any particular member or part thereof.

In a loose-leaf binder embodying the present invention, the stresses set up by the tightening operation are not confined to one bar, neither are the stresses distributed over the whole of the cover, but are distributed between one of the cover sheets, for example the backing sheet and the back edge of the cover.

A further object of the present invention is to provide improved components in the type of binder above referred to.

Another object of the present invention is to provide a loose-leaf binder which possesses manufacturing economies, while at the same time there is provided a strong and desirable construction of binder with an absence of intricate parts.

The accompanying drawings show by way of example only, a loose-leaf binder embodying the present improvements.

In the drawings:—

Fig. 1 is a plan view with the outside or front face of one cover removed, Fig. 2 a part sectional elevational view, while Fig. 3 is an end sectional view of the backing plate and allied parts.

Each cover is made up of side edges 1, 2 and a stretcher 3 forming the front edge, an inside or backing sheet 4 bent over at one end to form the back edge 5 and an outside or front board or sheet 6.

The thrust bearing 7 for the thong stretcher bar 8 is secured to the inside or backing sheet 4 of one cover, and the thongs 9 or the equivalent are anchored to the inside or backing sheet of the other cover.

The clamping members 10 are of strip-like form with slots 11 therein for the thongs 9 to pass therethrough. These clamping members may be made of aluminium.

In the example illustrated all the fitting

work for the thong mechanism is carried out on the inside or backing sheet.

The side edges 1, 2 and stretcher 3 are made of wood and the outside or front 6 of 60 plywood.

The inside or backing 4 is of sheet metal, for example sheet steel, bent over at one end to form the back edge 5, and extending under the outside or front board 6.

All these components are suitably secured together as by pins or rivets to form a chambered cover.

The bent over parts of the inside or backing sheets are slotted to permit the passage of the thongs.

In the chamber of one cover the thong stretcher bar 8 is placed, the actuating spindle 12 therefor being mounted in the thrust bearing 7 which is attached to the 75 inside or backing sheet of this cover, a plain bearing 13 for the spindle being provided at the bent over end of the backing sheet, as by turning-down a part thereof. The front edge of this cover is holed at 14 for 80 the insertion of an operating key. The actuating spindle 12 is not attached to the front edge, but is free thereof.

It will be seen that the backing sheet 4 and the back edge 5 made up in one-piece, 85 are all that is necessary to take the stresses set up by the winding mechanism, and that the other components completing the cover do not function for this purpose, that is to say, the stresses set up by the winding 90 mechanism are not distributed over all the components but are confined to two of the components.

In certain cases, especially with large size binders it may be desirable to reinforce or 95 strengthen the trough like back edge.

There are various ways of carrying out this reinforcement or strengthening provision.

One way is to provide a number of risers 100 or piers upstanding from the main part of the backing sheet. Another way is to provide a liner or strip extending longitudinally of the bent over part of the backing sheet. Another way is to provide bridge 105 pieces upstanding from the main part of the backing sheet. Another way is to reinforce the bent over part itself by attached pieces or strengthening ribs.

Another way is to provide in the chamber 110 a separate metal or other strip 15 having its ends located between the backing sheet 4

and the side edges 1 and 2 (see Fig. 1), and riveted or otherwise secured to the side edges. This strip is bent up so as to form bridges 16 through which or some of which 5 the thongs may pass, the tops of the bridges being in contact with the bent over part of the backing sheet, and the piers or risers being adjacent the thong-edges.

In this way there are provided channels 10 or passage-ways through which the thongs pass from the outside to the inside of the cover.

It is customary in this kind of loose-leaf binder for the outward limit of travel on 15 the screw thread or the equivalent of the stretcher bar away from the thrust bearing to be governed by the back edge itself acting as a stop, and this may result in the stretcher bar subjecting the back edge, especially when 20 of bent-up form, to subversive stress.

A stop 17 is provided on the actuating spindle so that the travel of the stretcher bar towards the back edge is limited.

According to one feature under the present invention the stretcher bar has a determined travel towards the back edge without becoming disconnected from the actuating mechanism so that the stretcher bar at the end of its movement away from the thrust bearing is stopped before it makes contact 30 with the back edge.

There are various ways of carrying out this feature.

Under the present invention provision is made to prevent binding between the inner edges and the clamping members. For this purpose the inner edge of each cover is cut back or bevelled away from the inside or backing sheet so as to provide a clearance. 35 This cutting back or bevelling is shown at 40 20 and 21. This clearance also allows of a greater angular movement of the covers in opening.

With a binder made according to the present invention the sheets lie substantially flat 45 when the binder is opened out, the thongs being in substantially a straight line.

What I claim is:—

1. In a loose-leaf binder of the character described having thongs attached to a bar 50 adjusted by screw mechanism in one of the covers, a cover comprising a wall and a back edge formed as a one-piece component, and a front edge formed by a stretcher, the thongs passing through said back edge, and a thrust bearing for the winding mechanism being mounted on said integral component, so that the stresses due to tightening the thongs are confined to the wall and the back 55 edge integral therewith.

2. In a loose-leaf binder of the character

described having thongs attached to a bar 60 adjusted by screw mechanism in one of the covers, a cover comprising an inside sheet and a back edge formed as a one-piece component, a front sheet, and a front edge formed by a stretcher, the thongs passing through said back edge, and a thrust bearing for the winding mechanism being mounted on said integral component, so that 65 the stresses due to tightening the thongs are confined to the inside sheet and the back edge integral therewith. 70

3. A loose-leaf binder of the character described having a cover made up of components forming side edges and a stretcher forming the front edge, an inner wall and a back edge formed as a one-piece unit, and a front wall, a thong stretcher bar in said cover, the thongs passing out of said cover through the back edge, an actuating spindle for said stretcher bar, a plain bearing for said spindle, and a thrust bearing for said spindle, the said bearings being attached to 80 one of said walls. 85

4. A loose-leaf binder having a cover made up of components forming side edges and a stretcher forming the front edge, an inside wall bent over at one end only to form a back edge, and a front wall, a thong stretcher bar in said cover, an actuating spindle therefor, the thongs passing out of said cover through the said back edge, a plain bearing for said spindle and a thrust bearing for said spindle attached to the 90 inside wall. 95

5. A loose-leaf binder having a cover comprising components forming side edges and a stretcher forming the front edge, a wall and a back edge formed as a one-piece component, clamping members of strip-like form, sheet-engaging thongs passing through said back edge, a stretcher bar in said cover to which said thongs are attached, a screw spindle for moving said stretcher bar, a plain bearing for said spindle, said bearing being on said back edge, and a thrust bearing for said spindle, said thrust bearing being on said wall. 100 105

6. In a loose-leaf binder of the character described, a cover comprising a backing sheet bent over at one end to form the back edge, and a strengthening strip for said back edge secured to said cover, said strip having bridge portions, the spans of the bridge portions being in contact with the inner face of said back edge and serving as guides for binding thongs on which the loose sheets are retained. 110 115

In testimony whereof, I affix my signature. 120

WILLIAM VENNARD.
